UNITED STATES PATENT OFFICE.

WILLIAM Q. PFAHLER, OF LEIPSIC, OHIO.

MECHANICAL LUBRICATOR.

No. 829,171.

Specification of Letters Patent.

Patented Aug. 21, 1906.

Application filed April 16, 1906. Serial No. 812,018.

To all whom it may concern:

Be it known that I, WILLIAM Q. PFAHLER, a citizen of the United States, residing at Leipsic, in the county of Putnam and State of Ohio, have invented a new and useful Mechanical Lubricator, of which the following is a specification.

My invention relates to mechanical lubricators for positively feeding oil or more viscous lubricants, such as grease or tallow, to parts to be lubricated.

It has for its object to provide a device of this character which is capable of noiseless operation, by which the rate of feed of lubricant can be accurately and easily adjusted, and which includes various other improvements whereby the efficiency of the apparatus as a whole is improved.

For a detailed understanding of the invention reference is to be had to the following description, taken in connection with the accompanying drawings, and to the claims appended hereto.

In the accompanying drawings, which illustrate one embodiment of which the invention is capable, Figure 1 is a central longitudinal section of the lubricator, showing parts in elevation. Fig. 2 is a side elevation of a portion thereof. Fig. 3 is a plan view, and Figs. 4 and 5 are detail views.

Referring to the drawings, 1 represents the base-plate, and 2 the top plate, which are both provided with shouldered bosses 3, against the shoulders of which the ends of the plunger-cylinder 4 engage. The boss of the base-plate is provided with a hemispherical cavity which forms the head of the plunger-cylinder. Intermediate the head end of the cylinder and the shoulder of the boss is a gasket 5. Supported on the top plate 2 is a frame 6, forming a support for the mechanism for actuating the plunger 7. The cylinder is held between the top and base-plates by bolts 8, which also secure the frame 6 in position. The plunger 7 is secured to a threaded rod 8', which is provided with a keyway 9, with which a key 10, carried by the top of the frame, engages. Engaging the thread of the rod is a nut 11, whereby the plunger is moved in or out of the cylinder. The nut 11 is held from longitudinal movement by an abutment 12 at one end and the top of the frame 6 at the other end. The nut 11 is rotated by an intermittently-rotated shaft 13 through miter-gears 13', which multiply the power. The shaft 13 is suitably

journaled in the frame and carries at its outer end a worm-wheel 14, which is adapted to rotate therewith by means of a yielding dog or spring 15, engaging with a crank 16, keyed to the shaft, the construction of the dog being such that the crank can be actuated in one direction by a handle 17 without imparting motion to the worm-wheel.

Disposed over the worm-wheel and mounted in a frame 18 is a shaft 19, carrying a worm 20, which latter meshes with the wheel and is adapted to impart intermittent motion thereto. At the rear end of the shaft 19 is keyed a ratchet-wheel 21, that is actuated by pawls 22. Loosely pivoted on the shaft 20 is an oscillating arm 23, upon which one of the pawls 28 is mounted and which is adapted to receive motion from an eccentric or other moving part of the apparatus to which the lubricator is applied. The arm is connected to such eccentric or moving part by means of an adjustable block 24, which is adapted to be moved endwise of the arm in order to vary the effective length of the same, and hence the stroke of the plunger through the ratchet mechanism.

The block is provided with teeth which interlock with teeth 25 on the arm, which, in connection with the set-screw 26, securely hold the block in adjusted position. The upper pawl 22 is pivoted on an upright 27, carried by the secondary frame 18. The oscillating arm 23 and the upright 27 are each provided with a lug 28, in which is mounted a cushion-tipped set-screw 29, the tip of which may be a piece of rubber or a helical spring, and against which tip a stop 30 on the pawl is adapted to engage. The object of this construction is to prevent noise by the pawls when they engage the teeth of the ratchet-wheel. Each pawl is held in engagement with the ratchet-wheel by an extension-spring 31, attached to the pawl at one end and to the arm 23 in the case of the lower pawl and to the upright 27 in case of the upper pawl.

In order to render the actuating mechanism inoperative when the plunger has reached the limit of its stroke without disconnecting the oscillating arm from its actuator, the worm is adapted to be disengaged from the worm-wheel, so that no motion is imparted to the latter. For this purpose the secondary frame 18 is pivotally mounted on the main frame 6 on fulcrums 32 and is held in normal position by a dog 33, fulcrumed on

the main frame at 34. The secondary frame and dog are each provided with a compression-spring 35, that is under tension when the parts are in normal position. The upper end of the dog is formed with a nose 36, located in the path of an adjustable finger 37, carried at the upper end of the plunger-rod. This finger is so positioned that when the plunger reaches the limit of its instroke it will engage the nose of the dog and move it outwardly, so as to release the secondary frame and permit the same to tilt under the action of its spring. When the secondary frame is so released, the worm is disengaged from the wheel 14, so that the continued intermittent rotary motion of the worm, due to the continued operation of the apparatus that rocks the arm 23, will have no effect upon the plunger.

In order to withdraw the plunger, so that the cylinder can be recharged with lubricant, the crank 16 is turned separately, during which operation the dog 15 yields to the movement of the crank without hindrance.

After the crank has been turned sufficiently to move the plunger to its original position and the cylinder has been recharged the secondary frame is restored to its normal position and the dog 33 set to permit the lubricator to continue its operation. The cylinder is recharged through a port 38, adjacent the outer end thereof, which communicates with a suitable source of lubricant. As the plunger moves inwardly the lubricant is discharged through the outlet port or ports 39 in the head of the cylinder.

The plunger 7 is composed of two cup-shaped members arranged in telescoping position, the inner or lower one of which is provided with a circumferential flange 40, which forms a shoulder for the packing-rings 41, while the rim 42 of the outer member forms the other shoulder. The two parts of the plunger are held together by the nut 43 on the inner end of the plunger-rod and the nut 44, engaging the thread of the latter.

In accordance with the provision of the patent statutes I have described one embodiment of the invention; but I desire to have it understood that the apparatus shown is merely illustrative and that the invention can be carried out by other means.

What I claim as new, and desire to secure by Letters Patent of the United States, is—

1. The combination of a base-plate, a top plate, a cylinder arranged between them with its ends in engagement therewith, members extending from one plate to the other and connected therewith for securing the cylinder between the plates, a frame supported on the top plate and secured in place by the said members, a plunger in the cylinder, and means mounted on the frame for actuating the plunger.

2. The combination of a base-plate and a

top plate each provided with a shouldered boss, a cylinder engaging the shoulders of the plates, bolts extending from the base and the top plate for securing the cylinder in place, a supporting-frame carried by the top plate 70 which is also secured in place by the bolts, a plunger in the cylinder, and a means supported on the frame for actuating the plunger.

3. The combination of a plunger and cylinder, a supporting structure, a threaded plunger-rod, means arranged to prevent the rod from rotating, a nut for imparting longitudinal movement to the rod, a shaft mounted on the structure with its axis at right angles to the rod, means between the shaft and nut for imparting motion to the rod, a worm-wheel loosely mounted on the shaft, a crank secured on the shaft, means between the crank and wheel for locking the two together 85 for rotating in one direction, a worm meshing with the wheel, and a ratchet mechanism for rotating the worm.

4. The combination of a plunger and cylinder, a nut and screw for reciprocating the plunger, a worm and wheel, a shaft for the wheel, a speed-reducing gear in permanent mesh between the wheel-shaft and nut for moving the plunger in both directions, a means for rotating the worm, a pivotally-mounted support for the worm, and a device for releasing the support to disengage the worm from the wheel when the plunger reaches the limit of its stroke in one direction.

5. The combination of a plunger and cylinder, a screw and nut for reciprocating the plunger, a worm-wheel disposed with its axis at right angles to the screw for actuating the nut, a worm meshing with the wheel, a ratchet mechanism arranged to rotate the worm and adapted to be continuously operated, a movable support for the worm which normally holds the latter in mesh with the wheel, means for releasing the support to permit the worm to disconnect from the wheel when the plunger reaches the limit of its stroke, and a shaft for the worm-wheel rotatable in one direction independently of the latter for actuating the screw and nut to withdraw the plunger.

6. The combination of a plunger and cylinder, a main frame supported on the latter, a threaded plunger-rod, a nut mounted in the frame which engages the thread of the rod for actuating the latter, means for rotating the nut which is mounted on the frame, a secondary frame pivotally mounted on the main frame, an actuating mechanism carried by the secondary frame, a dog for holding the secondary frame in operative position, and a member carried by the plunger-rod for disengaging the dog and releasing the secondary frame when the plunger reaches the limit of its stroke.

7. The combination of a plunger and cylinder, a screw and nut for actuating the plunger, a worm-gear for rotating the nut, a ratchet-wheel connected with the worm, pawls for rotating the ratchet-wheel, and cushioned stops for the pawls.

8. The combination of a plunger and cylinder, a threaded plunger-rod, a nut for reciprocating the rod, a main frame, a worm-wheel mounted on the frame, gearing between the worm-wheel and the nut, a pivotally-mounted frame on the main frame, a worm carried by the pivotally-mounted frame and engaging the worm-wheel, a ratchet mechanism also carried by the pivotally-mounted frame and movable therewith, a dog for holding the main frame in its normal position, and means for releasing the dog to render the worm and wheel inoperative without affecting the ratchet mechanism when the plunger reaches the end of its stroke.

9. The combination of a plunger and cylinder, a worm-and-wheel mechanism, means intermediate the same and the plunger for actuating the latter, a ratchet-wheel connected with the worm, pawls coöperating with the ratchet-wheel, supports for the pawls, lugs on the supports, cushion-tipped adjustable stops carried by said lugs, and abutments on the pawls which engage the cushioned ends of the adjustable stops.

10. The combination of a plunger and cylinder, a worm-and-wheel mechanism for actuating the plunger, a ratchet-wheel connected with the worm, pawls for intermittently rotating the ratchet, an oscillating arm supporting one of the pawls, and having serrations, a stationary support for the other pawl, and a block on said arm by which the latter is adapted to be connected to its actuating mechanism, said block having serrations engaging those of the arm and being adjustable upon the arm to vary the range of movement of the latter.

11. The combination of a plunger and cylinder, a threaded plunger-rod, an actuating-

nut engaging the thread thereof, a main frame supporting the nut, a miter-gear for actuating the nut, a worm-wheel gear for actuating the miter-gear, a movable support for the worm mounted on the main frame, a mechanism for intermittently rotating the worm, a dog engaging the support for holding the same in normal position, a spring for moving the support when the dog is released to disengage the worm from the wheel, and an adjustable finger on the outer end of the plunger-rod which is adapted to actuate the dog when the plunger reaches the end of its stroke.

12. The combination of a plunger and cylinder, a threaded plunger-rod, an actuating-nut engaging the thread thereof, a frame supporting the nut, a shaft mounted on the frame, a gearing between the shaft and nut, a worm-wheel loosely mounted on the shaft, a crank on the shaft, means between the crank and wheel for locking the two together to rotate in one direction to move the plunger inwardly and for disconnecting the crank and wheel to permit the former to withdraw the plunger.

13. The combination of a plunger and cylinder, a longitudinally-movable and non-rotatable threaded plunger-rod, an actuating-nut engaging the thread of the rod, a plunger movable with the rod comprising two parts arranged in telescoping relation and one part being rigidly and the other adjustably secured to the rod, a packing assembled between the parts of the plunger, and a nut engaging the thread of the rod for adjusting the adjustable part of the plunger and holding the parts together and the packing under compression.

In testimony that I claim the foregoing as my own I have hereto affixed my signature in the presence of two witnesses.
